UNITED STATES PATENT OFFICE.

WILLIAM E. SOMERVILLE, OF COAL CITY, ILLINOIS.

ENGINE-TESTING DEVICE.

1,248,738.

Specification of Letters Patent.

Patented Dec. 4, 1917.

Application filed January 27, 1916. Serial No. 74,596.

To all whom it may concern:

Be it known that I, WILLIAM E. SOMERVILLE, a citizen of the United States, residing at Coal City, county of Grundy, and State of Illinois, have invented certain new and useful Improvements in Engine-Testing Devices, of which the following is a specification.

This invention relates to improvements in engine testing devices, and one of the objects of the same is to provide an improved combined electrical and mechanical device of this character for the purpose of readily ascertaining the condition of the engine, such as by means of a visual indication of the working pressure within the cylinder or cylinders or the condition of the ignition system, spark plugs or of the cause of the trouble.

10 A further object is to provide an improved device of this character wherein the electrical and mechanical testing means are compactly combined in a single structure and arranged in a convenient position for the operator.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating the invention and in which

35 Figure 1 is a diagrammatic view of an improved device of this character constructed in accordance with the principles of this invention and shown in connection with six engine cylinders.

40 Fig. 2 is an enlarged detail view partly in elevation and partly in section of the indicating mechanism.

Fig. 3 is a vertical sectional view taken on line 3—3, Fig. 2.

45 Fig. 4 is a diagrammatic view of the wiring shown in Fig. 2.

Fig. 5 is a view in elevation of a modified form of the invention.

Referring more particularly to the drawings, the numeral 10 designates the engine cylinders having the usual spark plugs 11.

Arranged in any suitable position is a chamber 12, which may be mounted upon a support 13, and communicating with the

chamber 12 is a pressure gage 14, having an indicator or hand 15 which co-operates with the graduations 16.

Leading from the interior of each of the cylinders 10 is a passage 17, and each of these passages has connection with the chamber 12, and arranged in each of the passages 17 is a controlling valve 18 and a check valve 19, so that when the respective valves 18 are open, the pressure from the cylinders 10 will be exerted through the chamber 12 to the indicator 14. The check valve 19 is provided to prevent the suction in the cylinders 10 from influencing the gage 14.

A relief valve 20 of any desired type, is provided for the chamber 12 so that after the test has been made, of any one or more of the cylinders, the relief valve 20 may be opened, preferably manually to relieve the pressure in the chamber 12.

Mounted upon the support 13 which carries the chamber 12 are contacts 21, 22, which are permanently spaced from each other to form jump sparks. The contact 21 is grounded preferably through the support 13 and cylinders 10 and electrically connected with the contact 22, which latter is insulated as at 23, is a conductor 24 arranged within which conductor are a plurality of make and break devices 25, 26, 27.

Leading from the respective spark plugs 28, 29, 30, 31, 32 and 33, are conductors 34, 35, 36, 37, 38 and 39, the terminal contacts being arranged upon the support 13.

The make and break devices 25, 26 and 27 are located in convenient positions as are also the terminal contacts so that any one of the make and break devices may be shifted so as to form an electrical connection between the contact 22 and the spark plugs 11, thereby completing the circuit to the contact 22 from the respective spark plugs on the engine cylinders.

If the spark plugs of the particular engine cylinder which is to be tested is operating correctly, there will be a visual indication of the same by a jump spark between the contacts 21, 22.

Thus it will be manifest that any of the spark plugs in any one of the engine cylinders may be tested by shifting the respec-

tive cutoff devices 25, 26, 27 so as to electrically connect the respective terminal contacts 34, 35, 36, 37, 38 or 39 with the spaced contacts 21, 22.

5 The operating condition of the cylinder as to pressure may be tested by means of the gage 14 and all that is necessary to accomplish this is to open the controlling valve 18 in the passage 17 which leads from the 10 chamber 12 to the engine cylinder to be tested.

The gage 14 may be of the ordinary and well known type, and when the controlling valve 18 is open it will be manifest that the 15 compression within the engine cylinder may be readily ascertained from the gage and also the explosion pressure may be obtained in the same manner.

The working condition of the interior of 20 the cylinder, the condition of the valves or the condition of the ignition system may be simultaneously obtained by means of the pressure indicating gage 14 and the jump sparks between the contacts 21, 22 or if desired, 25 the condition of the ignition system may be obtained independently of the pressure condition in the cylinder by simply closing the respective controlling valves 18 in the passages 17.

30 In order to render it possible to obtain the pressure condition within the cylinders and the condition of the valves, it is not desirable to produce a spark in the cylinders and in order to obviate this another make 35 and break device 40 is provided, preferably in the form of a switch which is electrically connected with the contact 22 and is adapted to be moved into and out of engagement or electrical connection with 40 the contact 21, so that when the make and break device 40 is adjusted so as to bridge the contacts 21, 22, they will be electrically connected, and then both of the contacts will be grounded so that there will be no 45 jump spark produced between the contacts 21, 22, nor will there be a spark produced by the spark plugs 11 in the cylinders.

The condition of the compression of the charge in the engine cylinder and the explosion pressure in the engine cylinder may 50 be readily ascertained by the amount of pressure indicated on the gage 14, for instance, the pressure method of testing the cylinder for ascertaining the compression 55 of the charge will be indicated on the gage to the extent of from sixty to eighty pounds, while the explosion pressure will be indicated on the gage to the extent of three hundred pounds or more.

60 In the form of the invention shown in Fig. 5, a flexible conductor 41 is electrically connected with the contact 22 and to the other end of the conductor is connected a handle 42 provided with a contact 43 so 65 that with this form, the ignition system may

be tested by simply moving the contact 43 into engagement with any one of the spark plugs 11.

With this improved construction it will be manifest that it is not only compactly 70 arranged, but that there is produced a combination electrical and mechanical testing device whereby either the pressure conditions in the cylinder may be tested or the condition of the ignition system tested separately or simultaneously, at the will of the 75 operator.

While the preferred forms of the invention have been herein shown and described, it is to be understood that many changes 80 may be made in the details of construction and in the combination and arrangement of the several parts, without departing from the spirit of this invention and therefore it is desired that the drawing herewith submitted be considered as being merely dia- 85 grammatic.

What is claimed as new is:

1. A combined electrical and mechanical testing device for explosion engines, said 90 device embodying a pressure chamber having communication with one or more engine cylinders, means for controlling such connections, a pressure gage communicating with the chamber, a pair of contacts spaced 95 to form jump sparks, one of said contacts being grounded, and means whereby the engine spark plugs may be electrically connected with the other of said contacts.

2. A combined electrical and mechanical 100 testing device for explosion engines, said device embodying a pressure chamber having communication with one or more engine cylinders, means for controlling such connections, a pressure gage communicating with 105 the chamber, a relief valve for the chamber, a pair of contacts spaced to form jump sparks, one of said contacts being grounded, and means whereby the engine spark plugs may be electrically connected with the other 110 of said contacts.

3. A combined electrical and mechanical testing device for explosion engines, said 115 device embodying a pressure chamber having communication with one or more engine cylinders, means for controlling such connections, a pressure gage communicating with the chamber, a pair of contacts spaced to form jump sparks, one of said contacts being grounded, and means whereby the engine spark plugs may be electrically connected with the other of said contacts, the 120 last recited means embodying a circuit make and break device.

4. A combined electrical and mechanical 125 testing device for explosion engines, said device embodying a pressure chamber having communication with one or more engine cylinders, means for controlling such connections, a pressure gage communicating with 130

the chamber, a pair of contacts spaced to form jump sparks, one of said contacts being grounded, means electrically connecting the engine spark plugs with the other of said contacts, and means for grounding the last recited contact.

5. A combined electrical and mechanical testing device for explosion engines, said device embodying a pressure chamber having communication with one or more engine cylinders, means for controlling such connections, a pressure gage communicating with the chamber, a pair of contacts spaced to form jump sparks, one of said contacts being grounded, means electrically connecting the engine spark plugs with the other of said contacts, and means for electrically connecting the spaced contacts at will.
10. 6. A combined electrical and mechanical testing device for explosion engines, said device embodying a pressure chamber having communication with one or more engine cylinders, means for controlling such connections, a pressure gage communicating with the chamber, a pair of contacts spaced to form jump sparks, one of said contacts being grounded, means electrically connecting the engine spark plugs with the other of said contacts, and means embodying a circuit make and break device for shunting the current around the said spaced contacts.
15. 7. A combined electrical and mechanical testing device for engines, said device embodying a pressure chamber having communication with one or more engine cylinders, cutoffs individual to the connections for con-

trolling them, a pressure gage communicating with the chamber, a pair of contacts permanently spaced to form jump sparks, one of said contacts being grounded, means for electrically connecting the other contact with the engine spark plug, and a circuit make and break device electrically connected with one of the said contacts and adapted to bridge the contacts for grounding both of the contacts.

8. A combined electrical and mechanical testing device for engines, said device embodying a pressure chamber having communication with one or more engine cylinders, cut-offs individual to the connections for controlling them, a pressure gage communicating with the chamber, a pair of contacts permanently spaced to form jump sparks, a circuit leading from one of the said contacts to the spark plug of each of the cylinders, a make and break device in each of the circuits, the other of the spaced contacts being grounded, and a circuit make and break device electrically connected with one of the said spaced contacts and adapted to be brought into electrical connection with the other of said contacts for bridging the contacts.

In testimony whereof I have signed my name to this specification, in the presence of two subscribing witnesses, on this 25th day of January, A. D. 1916.

WILLIAM E. SOMERVILLE.
